HERMANN GEWECKE, OF BERLIN, GERMANY.

METHOD AND APPARATUS FOR TRANSMITTING SIGNALS TO LOCOMOTIVES AND THE LIKE.

Application filed May 3, 1922. Serial No. 558,304.

To all whom it may concern:

Be it known that I, HERMANN GEWECKE, engineer, of German nationality, residing at

12 Hallesches Ufer, Berlin SW., Germany, have invented certain new and useful Improvements in Methods and Apparatus for Transmitting Signals to Locomotives and the like; and I do hereby declare the following to be a full, clear, and exact description 10 of the invention, of which the following is a specification.

The invention relates to a method and apparatus for transmitting signals to travelling trains by means of electric oscillations.

15 In the use of the hitherto known devices of this kind, either the locomotive or the train has been fitted with a receiver which could be affected by an outwardly arranged transmitter. These installations have in particular the disadvantage that the senders arranged at the various block stations which are bodily far apart must be provided with energy. A further disadvantage of the aforementioned devices consists in the fact 20 that it is difficult to transmit a signal to a definite train only and not to all the trains within the range of the electric waves. A still further serious disadvantage of the hitherto known devices is that the receivers 25 which are generally installed on the locomotive can be influenced by disturbances of strange senders, atmospheric disturbances or by masses of metal in the neighborhood of the line.

30 Similar to other solutions (except where the solutions are carried out in a wireless way) of the problem of transmitting signals to travelling trains, the present invention also utilizes the principle of weakening electric energy generated on the locomotive by auxiliary means arranged along the line. The invention involves a special mode of putting this principle into effect. The hitherto known solutions according to this 35 principle have the disadvantage that an unintended releasing of the signals may be caused to take place at certain places on the body of the line for example, by metal sleepers, points, or metal masses, such as 40 over-line bridges and the like, in case the electrical installation on the locomotive is affected in a ferro-magnetic way, and that, furthermore, an effective influencing can

only occur at a very small distance between devices located on the locomotive and the 55 body of the line respectively.

All disadvantages of the hitherto known solutions of this kind and also of the solutions of a wireless character are completely overcome according to the present invention 60 by arranging on the locomotive of the travelling railway train a generator for electrical oscillations and at certain places on the body of the line receiving circuits tuned to the frequency of these oscillations. 65

In the drawings which illustrate several exemplifications of the invention;

Fig. 1 shows an installation of apparatus according to the invention on a railway locomotive and on the line; 70

Fig. 2 is a diagrammatic representation of the apparatus shown in Fig 1;

Figs. 3 and 4 show suitable installations comprising different ways of arranging the signalling devices of the installations; 75

Fig. 5 shows a cathode tube installation, comprising an arrangement for separating the transmitting element of the installation, arranged in the frame of the locomotive, from the producer of oscillations; which together with the signaling device is arranged in an easily accessible manner in the cab. 80

Figs. 6 to 8 show cathode tube installations with condensers for equalizing the cable capacity of the oscillating circuit; and 85

Figs. 9 to 11 show other modified forms of installations embodying the invention.

Fig. 12 shows an arrangement for signalling trains of different classes at different distances from a stopping point. 90

In the exemplification of the invention shown in Fig. 1, A denotes a producer of oscillations, and B designates a device in connection therewith for the releasing of signals or for the performance of other work. The device C in the frame of the locomotive acts as an electro-magnetic coupling between the producer of oscillations A and the line-element D. If C approaches D, as seen in Fig. 2, the energy of the producer 100 of oscillations A acting on the inductorium C is altered by being coupled with the line circuit D tuned to its frequency. The character of the coupling between the coil devices C and D is such that the oscillating 105 energy in A is changed so that the signalling

device B is made to act. E and F denote switching devices which are in communication with the brake-lever of the locomotive or with a line signal respectively. The switches E and F can be operated to render the installation ineffective. By means of suitable known line switching devices, any of the line elements D can be rendered effective or ineffective to initiate the operation 10 of the signalling device B.

The use of electric oscillations for co-ordinating the element on the line and the device on the locomotive enables a sensitive tuning of the parts with regard to the frequency 15 of oscillation to be obtained, with the result that only an accurate receiving set on the locomotive tuned to the frequency of the line can receive the energy from the sender. The co-ordination of the parts of 20 the installation, in such an instance, is absolutely independent of the climatic conditions. There is thus assured an absolute freedom from disturbances for the action of the installation. As the apparatus of 25 the line consists of a definite number of windings and of a fixed capacity, a withdrawal of energy from the oscillating circuit on the train by means of metal parts which may lie along the line and, in consequence, an unintended response of the 30 signalling apparatus cannot occur, as transmission of high frequency can take place between two circuits only when they are accurately tuned with regard to each other. 35 As a generator of electric oscillations in the practice of the invention a cathode tube generator A (Fig. 3) is especially suited. Suitably the coupling of the cathode tube 1 with the circuit of oscillation 2 is so 40 effected that a relay-action is induced in the generator, upon withdrawal of energy from the oscillating circuit by the tuned circuit D in such a manner that the oscillations produced by the generator are stopped 45 or at least much reduced. In comparison with other producers of oscillations such as Poulsen's arc light or an alternating current machine, the cathode-generator, in addition to the above-described relay-effect, 50 offers still further advantages. As is well known, the arc-light must burn in a chamber filled with hydrogen, so that an observation of the arc light from the outside is impossible. Thus the engine-driver 55 when a signal has been given does not know, whether the signal is due to a communication from the line or to a failure of the producer of oscillations. In the case of a cathode tube, if a signal is due to failure 60 of the oscillation generator, such fact can be ascertained at once, as the conditions under which oscillations are produced by cathode tubes can be controlled at any time. If, for instance, the heating of the 65 filament fails, the failure is apparent from

inspection of the filament. The attendance of an arc-light generator is also considerably more complicated than that of a cathode generator. Finally, it must be pointed out, that in case of cathode tubes, disturbances are rare, whereas, in the case of an arc-light generator, in consequence of their complicated mode of working, the consumption of the carbon, etc., unintended oscillations of the arc light, by reason of disturbances, occur extremely often. Also the replacement of a destroyed generator having a cathode tube is much simpler than that of an arc light generator. Moreover, the cathode tube possesses the property of producing constant oscillations which are absolutely essential for the present purpose, whereas, the production of oscillations by means of an arc light is subject to variations. The production of absolutely constant oscillations and the previously mentioned relay action also constitute important advantages of the use of a cathode generator over the use of alternating current machines, since the regulation of the revolutions of such machines offers serious difficulties. 75 80 85 90 95

The signalling device B preferably comprises a relay B' which is normally arrested by the action of the oscillations in the generator A. However, when the energy in the sender circuit is decreased or disappears by coupling of the generator A with the line element D, the relay releases its armature and closes a circuit in which an optical or sounding signalling device is arranged. The response of the signalling device can be registered by a time recorder. As shown in Fig. 3, the armature R of the relay B' is connected in circuit with a bell 100 T and time recorder V. From the recordings of the time recorder, on the one hand, the fault of the driver can be proved when he has run past a stop signal although the apparatus responded properly, and, on the other hand, a failure of the installation 105 can be ascertained. 110 115 120 125 130

The practical construction of the signalling device can be effected in various ways. Suitably (see Fig. 4) the relay B' is arranged in the anode-line of the cathode generator A so that upon cessation or reduction of the oscillations in the generator and the concomitant change in the anode-current, the relay armature is released and the desired signal is given. By making the tubes and the oscillating circuits of suitable proportions, this alteration of the anode-current can be made particularly great, whereby a reliable response of the relay may be obtained. 125

The oscillations produced in the generator A are preferably sent through a frame coil (see Fig. 1, apparatus C) which has the advantage that it sends out oscillations chiefly in one direction that is in the di- 130

rection of the planes of the windings of the coil. By using a corresponding frame coil for the receiver or line circuit D, the absorption of energy by this circuit can be 5 considerably increased. For example if the coils C and D are arranged horizontally as shown in Fig. 1 of the drawings, with the frame coil C mounted on the locomotive so that its horizontal plane is close to the 10 horizontal plane of the line coil D, then as coil C approaches the coil D in the movement of the locomotive and finally reaches a position directly above it, there will be a 15 large absorption of energy by the coil D from the coil C and therefore from the oscillating circuit on the locomotive. This absorption of energy will, of course, decrease the current flow in the signaling relay and cause it to close the signalling 20 circuit.

As a suitable coil for the tuned oscillating circuit D arranged on the line an armored coil is, preferably, employed which is arranged in such a manner that it is 25 protected from becoming damaged by stones and the like. It may have the shape of an iron tube enclosing windings (see Fig. 1, D). In such a case, the tubular cover should not constitute a closed magnetic or electric circuit. This may, for 30 instance, be achieved by disconnecting the iron tubular ring at one or several places and by closing it again at such places by means of an insulating material.

By constructing the oscillating system in the shape of frame coils a number of advantages are attained which are of special importance for the present purpose. Such advantages are: small space, increase 40 of the effect, smallest losses of energy, greatest freedom from disturbance, and protection against mechanical or climatic influences. All these advantages combine to the important result of assuring the 45 long-continued efficient operation of the installation.

When using cathode tubes having back coupling as generators in ordinary intermediate circuit installations in consequence 50 of the arrangement of the tubes difficulties arise in practice with regard to the construction and the working of the apparatus in consequence of the arrangement of the tubes in direct proximity to the intermediate circuit. The present problem calls for the local separation of the intermediate circuit parts which, on the one hand, serve for the back coupling and tuning and, on the other hand, for the coupling with the line 55 element and also calls for the use of the most simple conduits for their connection. If ordinary cables were used for connecting the parts, the high cable capacity would act in a disturbing manner as, when operating at short wave lengths, the available

self induction of the intermediate circuit and the degree of coupling between it and the line element would be too small.

A solution of this problem is afforded by the arrangement of connections shown in 70 Fig. 5. It consists in dividing the self-induction serving in the case of ordinary connections the double purpose of back coupling and coupling with the secondary circuit, and thereby dividing the tension at 75 the tube into two self induction parts C' and C serving each purpose separately. With such an arrangement in consequence of the parallel arrangement of the two self inductions, the total inductivity of the intermediate circuit is considerably reduced for 80 equalizing the high cable capacity. Preferably and as shown, the arrangement is so organized that the tube 1 with the coil C' and the tuning condenser 3 (together—ap- 85 paratus A of Fig. 1) are arranged in the cab of the locomotive so that there is an easy access to them, and only the coupling coil C which does not require any attendance is located below in the frame of the locomotive. 90 An ordinary lead cable K having two conductors connects the two coils C' and C, and an extension of the sensitive grid conduit is not required.

Equalization of the cable capacity of the 95 intermediate circuit can further be effected by arranging a shortening condenser L acting as a series-capacity in front of the coupling coil C and also, if desired, in connection with the line-element coil D.

Figures 6 and 8 show circuits including 100 such condensers.

Another solution of the aforementioned problem of enabling the apparatus serving for adjustment and requiring attendance to 105 be placed in the cab of the locomotive consists in providing a second circuit arranged on the locomotive and permanently coupled with the generator circuit. The second circuit is normally out of tune with the generator circuit with regards to its frequency, but upon being moved close to the line element, it is by means of an inductive or capacitive effect brought into resonance with the generator circuit, whereby the desired reaction 110 is obtained.

The inductive effect is illustrated in Fig. 9. The alternating current generator A¹ excites the primary oscillating circuit 12. The self-induction of the intermediate circuit 13 is divided into a part 4 intended to be coupled with the primary circuit 12 and into a part C intended to be coupled with the secondary circuit D. The tuning of the intermediate circuit with the aid of the adjustable condenser 5 is so chosen that the intermediate circuit is normally out of tune with the oscillating circuit 12. The coupling of the condenser with the secondary circuit D brings the intermediate circuit 125 130

into resonance with the primary circuit 2 whereby the desired release of the relay B' is caused to take place.

The capacitive effect is illustrated in Figs. 5 10 and 11. To the primary circuit a secondary circuit is permanently coupled, the tuning of which passes through a certain range when parts thereof approach electrical devices which are fixed at places in 10 the line where it is desired that signals shall be transmitted. When a locomotive carrying an element C, such as is shown in Fig. 10 or 11, passes a line element D of appropriate character, a condition of resonance is 15 set up between the primary and secondary circuits of the sender in the cab of the locomotive, thereby causing the intended release of the relay in the primary system to take place. In Figs. 10 and 11, L is the secondary circuit with the open condenser C, while D denotes an insulated condenser-plate serving as a line element. Upon C approaching D, the tuning range between the primary circuit and the secondary circuit is travelled through, and in the position of resonance (Fig. 10) the intended release in the primary circuit is effected. The arrangement according to Fig. 11 differs 20 from that shown in Fig. 10 only by connecting the condenser-plate D and one pole of the self-induction 4 of the secondary circuit with the earth so that the secondary circuit in the position of resonance is closed above earth. Although the invention has 25 been herein-before described as applied to trains, it will be understood that it may obviously also be applied to vehicles generally in the same manner as when used on trains for transmitting effects of any kind to them. 30 The generator is for instance mounted on the movable body and the means for influencing it (disengaging or releasing means) is fixed to suitable points in the path described by the body. 35 If it is, for instance, intended to draw the attention of the engine driver to an approaching signal on the line, an optical or acoustic signalling device is connected to the producer of oscillations. When the 40 train runs past the circuit (Fig. 1 D) which is on the line at a certain distance in front of the line signal, the train signal will be actuated.

The invention also permits allowance to 45 be made in the simplest manner for the different lengths of braking distances of the various kinds of trains. It is only necessary to arrange for a different tuning of the cathode generators and the releasing 50 means, that is to say, of the tuned secondary circuits, in order to effect transmission of signals to trains of certain speeds and to exclude trains which are operated at other speeds. In front of the point at which the 55 trains in case of a stop signal must be

brought to a stand still are arranged releasing circuits spaced from the stopping point by distances corresponding to the maximum lengths of the braking-distances for the various kinds of trains, each of the release circuits being tuned to the wave characteristic for the respective kind of train. A passenger train will therefore for instance only respond to the line circuits intended for such trains and not to the line circuits of fast 75 trains or goods trains. If in special cases a locomotive should be used for several kinds of trains re-adjustment of the wave length of its oscillation generator would have to be effected. This method of signaling trains 80 having different braking distances is illustrated diagrammatically in Fig. 12 in which 16 indicates the track and 15 a locomotive carrying an oscillation generator A', signal B' and inductance C', similar to like parts 85 shown in Fig. 3. S represents the point at which it is desired to stop all trains. It is obvious that trains of different classes have different braking distances, that is, swiftly moving passenger trains must have their 90 brakes applied before slower moving trains in order to cause all to stop at the same point. The tuned circuits D', D'' and D''', all tuned to different frequencies, are placed along the track at different distances from 95 the stopping point. The circuit D' is tuned to a frequency corresponding to the devices carried by trains of the longest braking distance. D'' to devices of shorter braking distance and D''' to devices of trains of still 100 shorter braking distance. The circuits on the trains for which D''' is tuned will not respond to either D'' or D' nor will the circuits on the trains to which D''' is tuned respond to either D' or D''. The trains of 105 the different classes will therefore receive their signals at different distances from the stopping point so that their brakes may be applied immediately thereafter to bring them all to a full stop at the point S. Of 110 course the brakes could be controlled directly by the signaling relay if it were desired to make the control of the trains automatic.

The device according to the present invention may include, in addition to the frame coil of the generator circuit, an antenna H (Fig. 5) to which the generator can be connected at will as, for example, by a switch J. This device is of importance 115 in cases where a train for any reason is stopped on the open line. By making a connection with the antenna it is possible to enter into direct communication with stations or other trains on the line by means 120 of the telegraph or telephone. It goes without saying that in this case a receiver may also be arranged on the locomotive in order to enable perfect intercourse to be had with the stations. 125 130

I claim as my invention:

1. An apparatus for transmitting signals or other effects to traveling railway trains or other movable bodies by means of electric oscillations, comprising an oscillating current generator carried by the train, a coil on the line forming a closed oscillating circuit tuned to the frequency of the oscillations in the generator and arranged to be coupled to the oscillating circuit of the generator so as to withdraw energy from said circuit, said generator including a three-element tube and an oscillating circuit divided into a portion back-coupled to the grid of the tube and a second portion coupled with the line circuit, thus providing two self-inductance circuits serving the purpose separately of back-coupling to the grid and of coupling with the line circuit, and signalling means controlled by the energy produced by said generator.
2. An apparatus for transmitting signals or other effects to traveling railway trains or other movable bodies by means of electric oscillations, comprising an oscillating current generator carried by the train, a coil on the line forming a closed oscillating circuit tuned to the frequency of the oscillations in the generator and arranged to be coupled to the oscillating circuit so as to weaken the energy in said circuit, said generator including a three-element tube and an oscillating circuit divided into a portion back-coupled to the grid of the tube and a portion coupled with the line circuit, thus providing two self-inductance circuits serving the purpose separately of back-coupling to the grid and of coupling with the line circuit, a long lead cable connecting the two portions of said oscillating circuit, and signalling means controlled by the energy produced by the generator.
3. An apparatus for transmitting signals or other effects to traveling railway trains or other movable bodies by means of electric oscillations, comprising an oscillating current generator carried by the train, and having a coupling coil, a coil on the line forming a closed oscillating circuit tuned to the frequency of the oscillations in the generator circuit and arranged to be coupled with the coil in the generator circuit so as to weaken the energy produced by the generator, a shortening-condenser located in front of the coupling coil of the oscillating circuit for equalizing the high cable capacity of said circuit, and means controlled by the energy produced by said generator for giving a signal.
4. A method of transmitting signals to trains which consists in classifying the trains in accordance with the distances with which they may be stopped when traveling at their normal speeds, providing trains of different classes with oscillation generators of different tuning and those of the same class with oscillation generators of like tuning, and providing signal releasing circuits at different distances in front of the point at which it is desired to bring the trains to a standstill in case of a stop signal, each of the releasing circuits being tuned to co-act with the oscillation generators of trains of one class only and being spaced from the stopping point by a distance corresponding to the maximum length of the braking-distances of trains of such class.

In testimony whereof I have signed my name to this specification in the presence of two subscribing witnesses.

HERMANN GEWECKE.
